(57) **CLAIM**

What is claimed is the ornamental design for a sleepwear breast pad pocket, as shown and described.

DESCRIPTION

FIG. 1 is a perspective view of a sleepwear breast pad pocket, showing the new design;

FIG. 2 is a front elevational view thereof, the rear elevational view being a mirror image thereof;

FIG. 3 is a cross-sectional view thereof, taken generally along lines 3-3 of FIG. 2;

FIG. 4 is a right-side elevational view thereof;

FIG. 5 is a left-side elevational view thereof; and,

FIG. 6 is a top plan view thereof, the bottom plan view being a mirror image thereof.

The broken lines showing a person wearing sleepwear and a second sleepwear breast pad pocket in FIG. 1 are included for the purpose of illustrating the invention in use, and form no part of the claimed design.
